SEAMLESS TUBE REELING

Ralph B. Wiley, McKeesport, Pa., assignor to National Tube Company, a corporation of New Jersey

Application January 3, 1940, Serial No. 312,309

2 Claims. (Cl. 30—13)

This invention generally relates to the manufacture of seamless steel tubes but it is particularly concerned with the step of reeling the tubes and with the machines used in carrying out this step.

In explanation, the manufacture of seamless steel tubes includes heating a solid steel billet to forging temperature and piercing this billet by passing it through a seamless tube piercing mill, the rough shell resulting from this step being then passed through a seamless tube rolling mill which works the shell to a wall thickness, length and diameter approximating what is desired in the way of a finished tube. However, the inside and outside finish of the tube form lacks smoothness and the wall thickness is somewhat irregular. It is the function of the reeling step to finish the surfaces of the form and to adjust its wall thickness. After this step the form is sized and finished by processing which depends on the demands the ultimate tube must meet.

A reeling machine is used in accomplishing this reeling step. In accordance with the teachings of the prior art, such a machine comprises a pair of cylindrical rolls between which a cylindrical mandrel is positioned. These rolls are arranged in axially crossed relationship so that when they revolve they work the tube form over the mandrel, the usual arrangement being for the axes of the rolls to bisect each other with the mandrel positioned centrally in line with the bisecting axes. Since the rolls and mandrel are all cylindrical, the rolls and mandrel work the tube form in a very localized manner, the rolls theoretically having only point contact with the form. As a result of this, the feeding speed of the form must be very slow so that the spirally rolled portions of the surfaces can properly overlap and result in a finished piece of work.

A seamless tube reeling machine constructed in accordance with the present invention is distinguished from such prior art machines by having axially crossed rails positioned and contoured to provide oppositely spaced revolving surfaces that mutually converge to form a gorge in line with the transverse axial intersection of the rolls and which then diverge from this gorge, a mandrel being positioned between the diverging portions of the roll surfaces and the surface of the mandrel and these diverging portions of the roll surfaces being respectively contoured to mutually provide a reeling pass bonded by mutually parallel revolving surfaces of substantial lengths. A reeling machine having its rolls and mandrel contoured as described results in the inside and

5 outside of a tube form passed through the machine, being reeled between opposite parallel surfaces forming line contacts extending diagonally along the tube. In other words, the reeling machine of the present invention works the tube form as though the machine were finishing flat strip having parallel surfaces excepting that this strip is in the form of a helix. Due to the 10 width of the strip, the tube form can be fed at relatively high speeds without losing the necessary overlapping relationship required to properly finish the work.

15 It is preferred to make the rolls of the barrel-type, the converging portions being conical with the gorge forming the bases of these portions. Theoretically, the diverging portions and the mandrel providing the cooperating working surface for these portions, should have very slightly curved contours to maintain a parallel pass, this 20 following from the fact that the rolls are necessarily axially crossed to provide for feeding of the work. However, under practical working conditions, it has been found sufficient to make the diverging portions of the surfaces of the rolls, 25 conical and to make the mandrel conical, the angularity of the respective conical surfaces being calculated as required to approximate parallelism of the various surfaces. It is possible to obtain 30 parallelism to an extent of less than a five minute deviation, and wearing of the surfaces soon causes the slight curvatures required for exact parallelism between the surfaces. In no case should the respective surfaces depart from 35 parallelism more than one-half a degree, if the desired effect is to be realized.

40 As previously explained, the result of using the new reeling machine is to enable working of the inside and outside of the tube form resulting from piercing and rolling operations, between spaced, mutually parallel surfaces of substantial lengths revolving diagonally of the form. These surfaces should not depart from mutual 45 parallelism more than one-half of a degree at the most. By calculating the roll contours and the contour of the mandrel so as to provide parallel surfaces rolling diagonally of the tube form when the rolled axes are crossed at greater angles than is usual in reeling machines, and by making the converging portions of the surfaces 50 of the rolls which lead to the gorge so as to properly enter the tube form into the reeling pass, it is possible to reel tubes much faster than could be done heretofore while obtaining a proper finish and a uniform wall thickness.

55 A specific example of the following disclosure

is illustrated by the accompanying drawing, in which:

Figure 1 shows the rolls in elevation;

Figure 2 is a section taken from the line II--II in Figure 1; and

Figure 3 is a section taken from the line III--III in Figure 2.

More specifically, the rolls 1 are illustrated as being of barrel type although properly contoured disk rolls could be used. The contour of these rolls is such as to provide the oppositely spaced revolving surfaces 1^a that mutually converge to the gorge 1^b located in line with the transverse axial intersection of the rolls, and the diverging surfaces 1^c which are calculated in conjunction with the surface of the mandrel 2 located between the rolls 1, to provide a reeling pass bounded by parallel rolling surfaces as indicated at 3, this pass being of substantial extent so as to work a helical strip of the tube form wall 4. It is to be understood that appropriate guides 5 must be used to position the form between the rolls 1.

When the form 4 encounters the surfaces 1^a, it is worked to an oval cross section and is then gradually returned to cylindrical form as it travels through the reeling pass 3. It is to be understood that the wall thickness of the tube form does not change to any great degree during its travel through the reeling pass 3, the effect being to take metal from parts of the wall that are too thick and to place this metal in parts of the wall that are too thin, whereby to even the wall thickness throughout. At the same time, a proper finish is imparted to the inside and outside of the form.

As previously explained, when the surfaces 1^c and surface of the mandrel 2 are conical, exact parallelism between the surfaces bounding the pass 3 is not obtained. However, it can be attained so completely that it is practically impossible to detect the deviation. The attainment of this relationship is done by regulating the angularity of the various conical surfaces with due re-

gard to the various factors involved. Although the surfaces 1^a are also shown as being conical and although this is considered preferable, it is conceivable that the surfaces might be slightly curved in some instances provided the contour is suitable for the purpose that must be accomplished, namely, the forming of the tube into an oval so as to apply some compression tending to slightly thicken its wall and so as to effect proper entry of the tube into the reeling pass of the rolls.

I claim:

1. A seamless tube reeling machine having axially crossed rolls positioned and contoured to provide oppositely spaced revolving surfaces that mutually converge to form a gorge in line with the transverse axial intersection of the rolls and which then diverge from this gorge, and a flaring mandrel between the diverging portions of said surfaces, the surface of said mandrel and said diverging portions of said roll surfaces being respectively contoured to mutually provide a reeling pass bounded by mutually parallel revolving surfaces of substantial lengths, whereby the inside and outside of a tube passed through said machine are reeled between opposite parallel surfaces forming line contacts extending diagonally along the tube.

2. A seamless tube reeling machine having axially crossed rolls positioned and contoured to provide oppositely spaced revolving surfaces that mutually converge to form a gorge in line with the transverse axial intersection of the rolls and which then diverge from this gorge, and a flaring mandrel between the diverging portions of said surfaces, the surface of said mandrel and said diverging portions of said roll surfaces being respectively contoured to mutually provide a reeling pass bounded by revolving surfaces of substantial lengths which do not depart from mutual parallelism more than a half of a degree.

RALPH B. WILEY.
